Application July 20, 1943, Serial No. 495,416

11 Claims. (Cl. 200—68)

1

The invention relates to circuit breakers and more particularly to air circuit breakers of low voltage and high current rating, for example, having voltage ratings up to 600 volts alternating current, and current ratings from several hundred amperes upwards to several thousand amperes.

Circuit breakers of the class described frequently require overload tripping means which will give a time delay prior to initiating tripping of the breaker on overloads up to a predetermined magnitude. A thermostatic element of the bimetallic type is particularly suited for the time delay feature as it provides a time delay which varies inversely as the magnitude of the current. However, due to the large currents involved, it is a difficult problem to properly heat the bimetal element in response to the current. The usual methods of heating the bimetal trip elements have not been found satisfactory. Heating the bimetal element by shunting a small portion of the current therethrough is unreliable because it is difficult to obtain the proper ratio of current flow through the bimetal elements. Heating the bimetal element from a heating portion of a series conductor requires a high temperature bimetal element and results in an undesirable concentration of heat or hot spot in the circuit breaker.

An object of the invention is the provision of a circuit breaker of high current rating with an improved overload trip device of simple construction which is accurate and reliable in operation and inexpensive to manufacture.

Another object of the invention is the provision of a circuit breaker of high current rating with an improved overload trip device comprising a series magnetic tripping means and a bimetal trip element heated indirectly in response to the current flow for controlling operation of the magnetic tripping means at least for overloads up to a predetermined magnitude.

Another object of the invention is the provision of a high current circuit breaker with an improved overload trip device comprising a series magnetic tripping means, the operation of which is controlled, at least for overloads up to a predetermined magnitude, by a low temperature bimetal element heated in response to the current flow by a partial turn conductor linking the magnetic circuit of the magnetic tripping means.

Another object of the invention is to provision of a high current circuit breaker having a series magnetic tripping means controlled by a low temperature bimetal element heated by a loop conductor which links the magnetic circuit and has a gap therein across which one end of the bimetal element is secured.

Another object of the invention is the provision of a high current circuit breaker with an improved overload trip device comprising a series magnetic tripping means having a normally

2

latched armature adapted to be released in response to overload currents by an ambient temperature compensated low temperature bimetal trip element heated inductively from the current of the magnetic tripping means.

Another object of the invention is the provision of a circuit breaker with an improved overload trip device employing a bimetal element heated in response to the current of the circuit for initiating tripping of breaker, and a very simple calibrating and adjusting means for adjusting the minimum overload tripping point of the circuit breaker.

The novel features that are considered characteristic of the invention are set forth in particular in the appended claims. The structure and mode of operation of the invention, together with additional objects and advantages thereof, will be best understood from the following detailed description of one embodiment thereof when read in conjunction with the accompanying drawings in which:

Figure 1 is a vertical sectional view of a circuit breaker embodying the invention, the view being taken on an irregular section line along the center pole of the breaker with parts broken away and with the trip device shown partly in section to illustrate the construction thereof.

Fig. 2 is an enlarged fragmentary sectional view showing the trip device.

Fig. 3 is a bottom view of the lower part of the trip device on the same scale as Fig. 2.

Fig. 4 is an enlarged front elevational view of the bimetal trip element and heater.

Fig. 5 is a plan view of the bimetal trip element and heater.

Figs. 6 and 7 are enlarged views of the scale plate of the trip adjusting means.

Fig. 8 is an enlarged view of the notched washer with which the scale plate cooperates, and

Fig. 9 is a fragmentary front elevational view showing the adjusting knob and scale plate.

The invention is illustrated as applied to a circuit breaker of the type disclosed in Patent No. 2,414,526, issued Jan. 21, 1947 to Merl E. Horn et al. and assigned to the assignee of the present invention. Some of the features of the trip device disclosed in this application are disclosed and claimed in the above mentioned copending application.

Referring to Fig. 1 of the drawings, the high current circuit breaker illustrated comprises a base 11 of insulating material on which is mounted three identical pole units, only the center pole unit being shown. The contact means of all of the pole units are adapted to be simultaneously operated by a single operating mechanism indicated generally at 13 located at the center pole.

Each pole of the circuit breaker has terminal members 15 and 17, and high current capacity

contact means comprising stationary main contacts 19 and 21 mounted respectively on terminal 15 and on a block 23 of conducting material, a tiltably mounted spring biased auxiliary contact member 25, a bridging contact 27 for bridging main contacts 19 and 21, and an auxiliary contact member 29 for engaging auxiliary contact member 25. The latter contact members have intermediate contacts 31-33 and arcing contacts 35-37 thereon which open in sequence shortly after parting of the main contacts upon opening of the circuit breaker. The bridging contact 27 and the auxiliary contact member 29 are carried by a yoke shaped switch member 39 which is pivoted at its lower end on a main frame 41 between the sides thereof by a pivot pin 43. The frame 41, the terminals 15 and 17, and the conducting block 23 are secured to the base by screws. The bridging contact 27 is mounted for limited movement on the switch member 39 and is backed by a spring to provide contact pressure in the closed position of the breaker. A flexible shunt conductor 45 connects the auxiliary contact member 29 to the upper terminal 15, and another flexible shunt conductor 47 connects the movable auxiliary contact member 29 and the bridging contact 27 to the conducting block 23. This block 23 is in turn electrically connected through the energizing winding of the trip device of the corresponding pole to the lower terminal 17.

An arc extinguisher 51 preferably of the spaced plate de-ionizing type is associated with the auxiliary contact means of each pole of the circuit breaker for quickly extinguishing arcs drawn by the arcing contacts upon opening of the circuit breaker.

The common operating mechanism 13 for simultaneously operating the contact means of all of the poles is mounted on the frame 41 of the center pole unit. This mechanism includes a lever 53 pivoted by a pin 55 on the upper end of the frame and connected by a link 57 to the center pole switch member 39. The lever 53 is releasably connected by a series of latches 59 and 61 to a closing lever 63 which is also pivoted on the frame by the pivot pin 55. The latches 59 and 61 are pivotally supported on the lever 53 between the sides thereof, and the latch 61 is normally held by the trigger latch 59 in latching engagement with a latch roller 65 on the closing lever. A latch 67 pivoted on a shaft 69 supported on the frame 41 engages the latch roller 65 to hold the closing lever latched in closed position. The latch 67 is biased to latching position by a spring 71.

The two outer pole units (not shown) each have a lever similar to the lever 53 of the center pole except not provided with any latching means. These levers of the two outer poles are pivoted on the individual frames of the two outer pole units similar to the frame 41 and are connected to the outer pole switch members by links similar to the link 57. The levers are all mechanically connected for simultaneous movement together by means of a tie bar 73 of insulating material fastened to the three levers. It will thus be seen that the movable contact means of all three poles are adapted to be simultaneously operated together by the single operating mechanism.

The circuit breaker is biased to open position by means of a plurality of accelerating springs 75 connected to the switch member 39 and to a portion of the frame. The circuit breaker is held latched in the closed circuit position by virtue of the main latch 67 which holds the closing lever

63 in position. Since the lever 53 is latched up to the closing lever, and is mechanically connected to the three movable switch members 39, these switch members and the contacts are thus held latched in closed position until the circuit breaker is tripped.

A trip bar 77 of insulating material is mounted on the shaft 69 and extends across the three poles of the circuit breaker. This trip bar has three spaced arms 79, one for each pole of the breaker. Each arm 79 extends to a position directly above the trip plunger of the corresponding overload trip device indicated generally at 81 so that when any one of the three trip devices is operated in response to an overload, the trip bar will be rotated to a tripping position to trip the circuit breaker. A trigger 83 on the center arm 79 of the trip bar is disposed to engage a curved tail piece of the trigger latch 59 and release the latches 59, 61 when the trip bar is actuated to tripping position by any one of the trip devices. Release of the latches 59 and 61 releases the lever 53 from the closing lever 63, and the opening springs 75 thereupon actuate the three movable switch members 39 and movable contacts of the circuit breaker to open position by rotating the lever 53 counterclockwise about pivot 55. This opening movement of the circuit breaker will occur even if the closing lever should be held down in its closed position. During the opening movement of the circuit breaker lever 53, a projection 85 thereon moves the main latch 67 to released position thereby releasing the closing lever. The closing lever 63 is biased upwardly by a spring (not shown) so that upon release of this lever it is moved in a counterclockwise direction about the pivot 55 to open position. During the latter part of the opening movement of the closing lever, the latch roller 65 re-engages the latch 61 and this latch and the trigger latch 59 are reset to latching position thereby re-establishing the connection between the closing lever 63 and the breaker lever 53. The circuit breaker may then be closed manually, or electrically by a solenoid (not shown), by rotating the closing lever 63 in a clockwise direction back to its closed position, whereupon it is again latched by the main latch 67 to hold the breaker in closed position. The trip bar 77 may be provided with a handle socket 87 for receiving a handle to manually trip the circuit breaker.

Referring to Figs. 1 and 2 and 3 each of the trip devices 81, there being one for each pole of the circuit breaker, comprises an electromagnet consisting of a stationary magnetic core 91, two movable magnetic cores or armatures 93 and 95, and an energizing conductor 97 forming one or more turns around the core members. The stationary core 91 has a threaded portion which is screwed into a threaded opening provided in a portion of the frame 41 to secure the core member to the frame. The larger core member or armature 93 slidably extends through an opening in the lower portion of the frame 41 and through a guide opening in the cross portion of a U-shaped frame 99. The frame 99 is rigidly secured to the bottom of the main frame 41 by a plurality of screws 101. This large armature 93 is normally held down by a latch 103 which is pivotally mounted upon a pivot pin 105 supported by the sides of the frame 99. The latch 103 engages an annular latch element 107 which is screwed into an opening in the lower end of the core 93. The latch insert 107 by virtue of its screw-threaded engagement with the core

member 93 provides a means for adjusting the air gap between the movable core 93 and the stationary core 91. Screwing the element 107 in or out relative to the core 93 serves to lower or raise the core 93 to change the air gap of the electromagnet. The upper end of the insert provides a circular latch shoulder engaged by the latch 103.

The smaller movable core member or armature 95 serves for instantaneous tripping of the circuit breaker upon the occurrence of overloads in excess of a predetermined magnitude, for example, above eight to ten times the normal rated current of the circuit breaker. This smaller core member rests loosely in a recess provided in the larger movable core member 93. Secured to core member 95 is a trip rod or plunger 109 which extends upwardly through an opening in the stationary core. This trip plunger 109 is moved upwardly to trip the circuit breaker when either movable core member 93 or 95 is pulled up to attracted position against the stationary core upon actuation of the trip device.

The energizing conductor 97 of the electromagnet is electrically connected at its upper end to a side of the conducting block 23 and at its lower end to the lower terminal member 17. Coil 97 is thus connected in series with the contacts of the corresponding pole of the circuit breaker, so that the current flow through the breaker energizes the electromagnet. The design of the electromagnet is such that the normal rated current produces sufficient magnetic pull to move the larger movable core member 93 upwardly to attracted position if this core member is released by the latch. The core 93, however, is normally held down by the latch 103, and this latch is adapted to be moved to released position to release the core member after a time delay in response to overload currents up to the aforementioned predetermined magnitude, by means of a current response thermal trip element. Although the small core member 95 is free to move upwardly independently of the larger core member 93, the magnetic pull of the electromagnet is insufficient to move the small core upwardly to attracted position except upon the occurrence of heavy overload currents in excess of the predetermined magnitude at which instantaneous tripping of the circuit breaker is desired.

The circuit breaker and the electromagnet structure as thus far described in detail above is substantially similar to that disclosed in the aforementioned Patent No. 2,414,526.

In accordance with the present invention, time delay tripping operation of the circuit breaker is controlled by a bimetal element 110 which is inductively heated from the current flow through the energizing conductor 97 of the electromagnet through the agency of a loop conductor 111 linking the magnetic circuit of the electromagnet. The loop conductor 111 (Fig. 5) comprises a flat incomplete washer or ring of conducting material having a gap 113 between its opposed ends. The conductor 111 encircles the stationary core 91 of the electromagnet as shown in Fig. 2 and is clamped or secured to the intermediate cross portion 115 of the frame 41 between this portion of the frame and the energizing conductor or winding 97 of the electromagnet. The conductor 111 is insulated from the frame and from the conductor 97 by a pair of insulating washers 117 and 119. The bimetal element 110 comprises a strip of bimetallic material of the low temperature type composed of

two or more strips of metal having dissimilar coefficients of expansion, bonded together into one strip which warps or deflects upon being heated a predetermined amount. The bimetal element is of the so-called low temperature type which will warp in response to a relatively moderate heating thereof as compared to high temperature bimetals which must be heated to a high temperature before deflection will occur.

5 The upper end of the bimetal element 110 is bent angularly and is rigidly secured by a plurality of rivets 121 to the opposed ends of the loop conductor 111 in bridging relation across the gap 113, thereby completing a path for current flow through the loop conductor and through the portion of the bimetal element which bridges the gap 113. Adjacent its upper end, the bimetal element is held in clamped relation against a portion of the frame by a clamp 123 and a pair of screws 125, the bimetal being insulated from the clamp and the frame by spacers 127 and 128 of insulating material.

The bimetal element 110 is heated in response to overload current through the circuit breaker by 25 current flow through the loop conductor 111 and a portion of the bimetal element which bridges the gap 113 therein induced from the magnetic flux of the electromagnet. When heated a predetermined amount in response to overload current, the bimetal trip element 110 warps or deflects inwardly to engage and move an ambient temperature compensating bimetal element 131 fastened to a pivoted U-shaped lever 133 which is connected to the latch 103 by a connecting link 135. The deflecting movement of the bimetal trip element 110 is thus transmitted to the latch 103 causing the latch to release the movable core 93 whereupon core 93 is moved upwardly to attracted position to trip the circuit breaker. An insulating button 137 secured to the upper end of the ambient temperature compensating bimetal element serves to insulate these elements from one another. The bimetal element 131 serves to compensate the device for changes in ambient temperature so that the overload tripping point of the breaker will not be affected by changes in ambient temperature.

The lever 133 is pivotally mounted on a pivot pin 139 which is guided for slidable movement 50 in a pair of slots 141 in the sides of the frame 99. The pivot pin 139 is held in fixed position in the slots 141 by an adjusting means herein-after described. The connecting link 135 is pivotally connected to the lever 133 by a pivot pin 143 and to the lower end of the latch 103 by a pivot pin 145. A spring 147 having portions coiled around the pivot pin 139 serves to bias the lever 133 in a clockwise direction as viewed in Fig. 2 about its pivot 139 to restrain the latch 103 in 55 latching position.

A very simple calibrating and adjusting means is provided for calibrating the trip device and for adjusting the minimum overload current value at which the bimetal trip element 110 will initiate tripping operation of the circuit breaker. This adjusting means comprises a rotatable knob 149 (Fig. 2) of insulating material having a shaft 151 rigid therewith which extends through an opening provided in the frame 99. The inner portion of the shaft is provided with a left-hand screw thread which screws into a nut 153 which pivotally engages the pivot shaft 139 of the lever 133. The nut 153 is disposed between the sides of the lever 133 and has a transverse opening 70 through which the pivot shaft 139 extends. A

helical compression spring 155 disposed between the nut 153 and the front portion of the frame 99 serves to bias the connected knob and nut 153 inwardly and to hold these elements in the position shown in Fig. 2, thereby holding the pivot shaft 139 in the position to which it has been adjusted. The shaft 151 of the nut is slideable and rotatable in the opening of the frame 99 through which it extends, and the knob is rotatable through substantially a single revolution to adjust the minimum overload tripping point of the trip device. Rotation of the knob 149 in a counterclockwise direction moves the nut 153 and the pivot shaft 139 outwardly away from the base 11, that is, toward the right as viewed in Fig. 2, due to the left-hand thread on the knob shaft. This outward movement of the nut 153 and pivot shaft 139 causes the lever 133 to pivot in a counter-clockwise direction about the pivot 143 as viewed in Fig. 2, thereby moving the upper end of the ambient temperature compensating bimetal element 131 farther away from the free end of the bimetal trip element 110. This increases the overload setting of the trip device due to the fact that the bimetal element 110 will have to be heated a greater amount and deflect a greater distance before it will release the latch 103 and thereby initiate tripping of the circuit breaker. Conversely, rotation of the manual adjusting knob 149 in a clockwise direction will effect movement of the nut 153 and pivot shaft 139 inwardly toward the base of the breaker thereby decreasing the distance between the free ends of the bimetal elements 110 and 131. This will decrease the minimum overload current at which the bimetal trip element 110 will effect release of the latch 103 to initiate tripping of the breaker. During adjustment, the pivot 143 remains fixed.

An annular scale plate 157 is disposed on the shaft 151 of the knob between the knob 149 and the front of the frame 99. This scale plate is normally locked to the knob as will be described later but is capable of being rotated relative to the knob to permit calibration of the breaker. The scale plate 157 is provided with a scale marked in percentages of overload current and has a projection 159 (Figs. 6 and 7) secured thereto which is adapted to engage a stop screw 161 mounted in the front portion of the frame 99. Since the scale plate is normally locked for rotation with the knob, the screw 161 and projection 159 serve to limit rotation of the knob to substantially one revolution. A washer 163 is disposed on the shaft 151 between the scale plate 157 and the front portion of the frame 99. This washer as shown in Fig. 8 has a hexagonally shaped opening which slidably engages the hexagonally shaped portion of the shaft 151 so that the washer is slideable relative to the shaft but is rotatable therewith. The periphery of the washer is provided with a series of notches 165 which extend completely around the circumference of the washer. These notches cooperate with a locking element or projection 167 secured to the inner side of the scale plate 157 to lock the scale plate to the washer for rotation with the knob 149. The projection 167 engages in one of the notches, thereby locking the washer and scale plate for rotation together. The notches 165 also cooperate with a small rounded projection 169 (Fig. 2) on the front side of the frame 99 to retain the adjusting means comprising the knob 149 in adjusted position. The spring 155 presses the knob 149 firmly against the scale plate 75

157 and washer 163 and presses these elements against the front portion of the frame 99. The spring 155 and notched washer 163 thus serve as a resilient notching device to retain the knob in adjusted position.

To calibrate the circuit breaker a given value of overload current is passed through the breaker and the knob 149 is rotated to a point where the bimetal trip element 110 releases the latch 103 in a given period of time. The knob 149 is then pulled outwardly against the tension of the spring 155 and the scale plate moved outwardly to disengage it from the locking washer 163. The scale plate is then rotated relative to the knob until the given overload current marking on the scale plate is in line with the index mark comprising the stop screw 161 on the frame 99. The knob is then released and the spring returns the parts to the position shown in Fig. 2. The projection 167 then engages one of the notches in the washer 163 and is thereby locked to the knob 149. As previously explained, adjustment of the minimum overload current at which the trip device will trip the breaker is accomplished by rotating the knob 149 in one direction or the other until the proper overload value on the scale lines up with the index 161. The pitch of the screw thread on the knob shaft is such as to provide a wide range of minimum overload trip settings.

While the invention has been disclosed in accordance with the patent statutes, it is to be understood that various changes in the structural details and arrangement of parts may be made without departing from some of the essential features of the invention.

We claim as our invention:

1. In an electrical circuit breaker, an overload trip device comprising an electromagnet energized by the current through the circuit breaker having a centrally disposed fixed core member and an axially movable core member operable when moved to attracted position to trip the circuit breaker, a latch normally restraining said movable core member, a thermally responsive element fixedly mounted at one end and operable when heated a predetermined amount in response to overload current to cause said latch to release said movable core member, means for heating said element comprising a fixedly mounted loop conductor surrounding said core members of said electromagnet and having a gap therein bridged by the fixedly mounted end of said thermally responsive element whereby said element is heated by current induced in said loop flowing through the bridging portion of said thermally responsive element.

2. In an electrical circuit breaker, an overload trip device comprising an electromagnet energized by the current through the circuit breaker having an armature operable when moved to attracted position to trip the circuit breaker, a latch normally engaging and restraining said armature, a thermally responsive element of bimetallic material having one end fixedly mounted and the other end deflectable when heated a predetermined amount in response to overload current to cause said latch to release said armature, means for heating said element comprising a loop conductor linking the magnetic circuit of said electromagnet and having a gap therein bridged by the fixedly mounted end of said bimetal element, and a second bimetal element operatively relating said thermally responsive element with said latch for compensating said trip device for variations in ambient temperature.

3. In an electrical circuit breaker, an overload trip device therefor comprising an electromagnet energized by the current through the circuit breaker having a magnetizable core structure and at least one armature operable when moved to attracted position to trip the circuit breaker, a latch for positively restraining said armature, a thermally responsive bimetal trip element operable when heated a predetermined amount in response to overload current to cause said latch to release said armature, means for heating said bimetal element comprising a loop conductor surrounding a portion of said core structure, said loop conductor being fixedly mounted relative to said core structure and having a gap therein, one end of said bimetal element being rigidly secured to the ends of said loop conductor across said gap, and means independent of said electromagnet for adjusting the minimum overload current at which said bimetal trip element will cause said latch to release said armature without affecting said bimetal trip element.

4. In an electrical circuit breaker, an overload trip device therefor comprising an electromagnet energized by the current through the circuit breaker having a magnetizable core structure and at least one armature operable when moved to attracted position to trip the circuit breaker, a latch normally restraining said armature, a thermally responsive bimetal trip element operable when heated a predetermined amount in response to overload current to cause said latch to release said armature, means for heating said bimetal element comprising a loop conductor surrounding a portion of said core structure, said loop conductor being fixedly mounted on said core structure and having a gap therein, one end of said bimetal element being rigidly secured to the ends of said loop conductor across said gap, and a second bimetal element operatively relating the latch to said bimetal trip element for compensating said bimetal trip element for variations in ambient temperature.

5. In an electrical circuit breaker, an overload trip device comprising an electromagnet energized by the current through the circuit breaker and having a magnetizable core structure and at least one armature operable when moved to attracted position to trip said circuit breaker, a latch normally restraining said armature against tripping movement, a thermally responsive bimetal trip element deflectable when heated a predetermined amount in response to overload current to cause said latch to release said armature, means for heating said bimetal trip element comprising a loop conductor surrounding a portion of said core structure, said loop conductor being fixedly mounted relative to said core structure and having a gap therein, one end of said bimetal trip element being rigidly secured to the ends of said loop conductor across said gap, and a second bimetal element operatively relating said latch with the free end of said bimetal trip element for compensating the device for variations in ambient temperature.

6. In an electrical circuit breaker, an overload trip device comprising an electromagnet energized by the current through the circuit breaker and having a magnetizable core structure including a stationary core and an axially movable core operable when moved to attracted position to trip the circuit breaker, a pivoted latch normally engaging and restraining said movable core, said latch having a fixed pivot, a thermally responsive bimetal trip element having one end fixedly sup-

ported and the other end deflectable when heated a predetermined amount in response to overload current to cause said latch to release said movable core, means for heating said bimetal trip element comprising a fixedly mounted ring of conducting material surrounding one of said cores and having a gap therein, said bimetal trip element being rigidly secured at said one end to the ends of said ring across the gap.

10. In an electrical circuit breaker, an overload trip device therefor comprising an electromagnet energized by the current through the circuit breaker and having a magnetizable core structure and at least one armature operable when moved to attracted position to trip the circuit breaker, a latch normally restraining said armature, a thermally responsive bimetal trip element operable when heated a predetermined amount in response to overload current to cause said latch to release said armature, means for heating said bimetal element comprising a loop conductor surrounding a portion of said core structure and having a gap therein, one end of said bimetal element being rigidly secured to the ends of said loop conductor across said gap, and adjusting means comprising an adjusting member separate from said bimetal element and insulated therefrom rotatable through substantially a single revolution to adjust the tripping point of said bimetal element without changing the position of said bimetal element.

8. In an electric circuit breaker, an overload trip device comprising an electromagnet energized by the current through the circuit breaker and having a movable armature operable when moved to attracted position to trip the circuit breaker, a pivoted latch normally restraining said armature against tripping movement, a pivoted lever, a connecting link connecting said latch and lever pivotally connected to each, a bimetal element separate from said lever heated in response to the current of the circuit and operable when heated a predetermined amount in response to overloads to engage and move said lever and thereby release said latch, and adjusting means comprising a manually operable adjusting member separate from said bimetal element rotatable through substantially a single revolution for adjusting the minimum overload current at which said bimetal element will release said latch, and a spring lock for retaining said adjusting member in adjusted position.

9. In an electric circuit breaker, an overload trip device comprising an electromagnet energized by the current through the circuit breaker and having a movable armature operable when moved to attracted position to trip the circuit breaker, a pivoted latch normally restraining said armature against tripping movement, a pivoted lever, a connecting link connecting said latch and lever pivotally connected to each, a bimetal element heated in response to the current of the circuit and operable when heated a predetermined amount in response to overloads to move said lever and thereby release said latch, and adjusting means comprising a manually operable adjusting member rotatable through substantially a single revolution for shifting the position of the pivot of said lever to adjust the minimum overload tripping point of said bimetal element.

10. In an electric circuit breaker, an overload trip device comprising an electromagnet energized by the current through the circuit breaker having a movable armature operable when moved to attracted position to trip the circuit breaker,

11

a pivoted latch normally restraining said armature against tripping movement, a pivoted lever, a link connecting said latch to said lever pivotally connected to each, an ambient temperature compensating bimetal element carried by said lever, a bimetal trip element heated in response to the current of the circuit and operable when heated a predetermined amount in response to overload current to move said compensating bimetal element and lever to release said latch, and adjusting means for adjusting the position of the compensating bimetal element relative to said bimetal trip element without changing the position of said latch to thereby adjust the overload tripping point of said circuit breaker.

11. A trip device for a circuit breaker comprising tripping means operable to trip the circuit breaker, a bimetal element heated in response to the current through the breaker and operable when heated a predetermined amount in response to overload current to initiate operation of said tripping means, a support, adjusting means comprising an adjustable element movable to vary the value of overload current at which said bimetal element will initiate operation of said tripping means, a rotatable knob having a shaft extending through an opening in said support and screw portion engaging said adjustable element, said knob being rotatable through substantially a single revolution to vary the position of said adjustable element, an annular scale plate on said shaft between said knob and support slidably and rotatable relative to said shaft, said scale plate

12

having an overload current scale cooperating with an index on said support, a washer on said shaft between said scale plate and said support slidably relative to but rotatable with said shaft, said washer having a series of openings therethrough disposed concentrically around said shaft cooperating with a projection on said scale plate to normally lock said scale plate for rotation with said shaft and knob and also cooperating with a rounded projection on said support to retain said shaft and knob in adjusted position, and spring means biasing said shaft and knob inwardly to maintain said washer, scale plate and knob pressed against said support, said knob and shaft being manually movable outwardly in axial direction against the tension of said spring means to unlock said scale plate and permit rotatable adjustment thereof relative to said shaft for calibrating the device.
